UNITED STATES PATENT OFFICE

MARTIN A. CALLAGHAN, OF BURLINGAME, CALIFORNIA

PARTITION CONSTRUCTION

Application filed April 4, 1929, Serial No. 352,415. Renewed May 31, 1930.

My invention relates to improvements in partition structures wherein studs mounted in pairs are held rigidly in spaced parallel relation by means of clip members engaging 5 said studs and provided with means for embracing an opposite clip member to secure the clip members upon the studs and brace the studs in rigid spaced parallel relation.

The primary object of my invention is to 10 provide an improved construction for partitions, and the like.

Another object is to provide an improved 15 partition structure wherein pairs of studs are rigidly secured and braced in spaced parallel relation.

A further object is to provide an improved 20 partition structure which may be easily and economically installed and which will facilitate the application of surfacing material of any suitable nature.

Another object is to provide an improved spacing clip for rigidly securing partition 25 studs in spaced parallel relation.

A further object is to provide an improved 30 spacing clip for partition structure which may be applied to secure the studs at top and bottom to suitable framing and to be applied also at desired intervals to secure and brace the studs of a partition.

35 A further object is to provide an improved spacing clip wherein clip members of identical form are adapted to be applied in oppositely facing relation to embrace studs from opposite sides and to be secured in interlocking engagement.

A still further object is to provide an improved clip which may be easily applied and which is simple, efficient, and economical.

I accomplish these and other objects by 40 means of the improved device disclosed in the drawings forming a part of the present application wherein like characters of reference are used to designate similar parts throughout the specification and drawings, and in which—

Fig. 1 is a broken horizontal transverse section of a portion of a partition embodying my improved structure;

Fig. 2 is a broken front elevation of a portion 45 of the structure, the surfacing material

being omitted and portions being broken away and shown in section;

Fig. 3 is a broken vertical transverse section showing the studs and spacing clips in elevation;

Fig. 4 is a perspective view showing the manner in which a pair of clip members are applied in oppositely facing relation;

Fig. 5 is a top view of a pair of clip members;

Fig. 6 is a side elevation of the pair of clip members with the extensions bent to embracing position;

Fig. 7 is a vertical transverse section showing the manner in which a pair of clip members are moved into engaging relation with a stud and with each other;

Fig. 8 is a similar view with the extensions bent to embracing position; and

Fig. 9 is a sectional view showing the manner in which one of the extensions of each of a pair of clip members may be secured to a framing member and the other extension bent to embrace the opposite clip member.

Referring to the drawings, my invention comprises a plurality of studs 1 mounted in spaced pairs to form the supporting structure of a partition or the like. Each stud preferably consists of a light metal channel 1' having a wooden filler adapted to form the main supporting member, the channel 1' of each stud being outwardly faced so that the outer face of the wooden filler is exposed.

The studs 1 of each pair are held rigidly in spaced parallel relation by means of spacing clips each consisting of a pair of clip members 2 formed from suitable sheet metal in the form of straps having the ends offset as at 3 to form stud engaging recesses. Extensions 4 are formed upon the portions of the straps intermediate the recesses 3, said extensions being formed adjacent one of the recesses 3 and at one side of the center of the member. The extensions 4 have openings 6 formed therein and are initially bent at substantially right angles to the plane of the intermediate strap portion to extend outwardly upon the upper and lower edges of said strap portion in the direction of the open side of the recesses 3.

The clip members 2 are applied in pairs to engage the pairs of studs 1 from opposite sides thereof. The members 2 are made identical in form, one of the members of each pair being merely inverted with respect to the opposite member whereby the extensions 4 of each member will extend across the intermediate strap portion of the opposite member in a direction opposite to the extensions of said opposite member, as best shown in Figs. 4 and 5. After the clip members are moved into operative position in engagement with a pair of studs 1, as shown in Fig. 7 of the drawings, the extensions 4 are bent to embrace the opposite member 2 as shown in Fig. 8, thereby effectually interlocking the members 2 and securing the same in engagement with the studs to brace the same and rigidly hold said studs in spaced parallel relation.

To secure the studs at their bases, the lowermost extensions 4 of a pair of clip members are caused to seat upon a suitable framing member or floor stud 7 and suitable securing members 8 applied through the openings 6 to secure the clips to said framing member, as shown in Fig. 9 of the drawings, the upper extensions 4 being bent to embrace the opposite clip members as shown. In like manner, the studs may be secured at the top by leaving the uppermost extensions 4 bent from their outwardly extending position to receive securing elements driven into an upper frame member in a corresponding manner.

The wooden fillers of the studs are exposed upon the outer faces of the studs, thereby permitting any suitable surfacing material such as wall board, lath, or moldings 9 to be applied and secured by nails, staples, or other securing means driven directly into said wooden fillers. The metal channels 1' may be formed from light sheet metal to face the back and sides of the studs and thus obtain a substantially fire proof construction. The wooden fillers afford adequate strength, and as thus faced by the light sheet metal channels, and braced by my improved spacing clips, may be constructed easily and economically to produce an improved inside partition.

Having thus described my invention, what I claim as new and desire to secure by Letters Patent is—

1. A partition structure comprising a plurality of studs mounted in pairs; and a plurality of spacing clips mounted at intervals along each pair of studs, said clips each comprising a pair of oppositely facing members recessed at the ends to engage the studs and provided with extensions formed intermediate of the recessed ends and bent into embracing relation with the opposite clip member for securing said members in interlocking re-

lation to rigidly hold the studs in spaced parallel relation.

2. A partition structure comprising a plurality of studs mounted in pairs; and a plurality of spacing clips mounted at intervals along each pair of studs, said clips each comprising a pair of spacing members having oppositely facing recesses formed at the ends thereof to engage opposite sides of the studs, the portions of said members intermediate of the recessed ends extending between the studs in proximate matching relation and being provided with extensions bent at right angles to said intermediate portions and extending across the opposite intermediate portion, certain of said extensions being secured to upper and lower framing members and the remaining extensions being bent into embracing relation to the opposite member to rigidly hold the studs in spaced parallel relation.

3. A partition structure comprising a plurality of studs mounted in pairs; and a plurality of spacing clips mounted at intervals along each pair of studs, said clips each comprising a pair of spacing members having oppositely facing recesses formed at the ends thereof to engage opposite sides of the studs, the portions of said members intermediate of the recessed ends extending between the studs in matching proximate relation and each being provided with extensions formed upon the edges thereof adjacent one of the recesses and bent at substantially right angles into parallel relation, the extensions of each member extending across the opposite member adjacent to and oppositely disposed relative to the extensions of said opposite member, some of said extensions being secured to a framing member, and the remaining extensions bent to embrace said opposite member to rigidly hold the studs in spaced parallel relation.

4. A partition structure comprising a plurality of studs mounted in pairs, said studs comprising outwardly faced metal channels provided with wooden fillers exposed upon the outer face thereof; and a plurality of spacing clips mounted at intervals along each pair of studs to rigidly hold the studs in spaced parallel relation, said clips each comprising a pair of spacing members having their ends offset to form oppositely facing recesses engaging opposite sides of the studs, the portions of each member intermediate of said recesses being provided with extensions extending across the opposite member to secure the clips in engagement with the studs.

5. A partition structure comprising a plurality of studs mounted in pairs, said studs comprising outwardly faced metal channels provided with wooden fillers exposed upon the outer face thereof; and a plurality of spacing clips mounted at intervals along each pair of studs to rigidly hold the studs in

spaced parallel relation, said clips each comprising a pair of spacing members having their ends offset to form recesses adapted to engage opposite sides of the studs, the portions of said members intermediate of said recesses being disposed in matching proximate relation and provided with extensions formed on the edges thereof and extending across the intermediate portion of the opposite member to embrace said portion and secure the clips in engagement with the studs.

6. In a partition structure, a spacing clip comprising a pair of spacing members each consisting of a metal strap having the ends offset to form recesses adapted to engage the sides of spaced studs, the portions of said strap intermediate of the recesses being provided with integrally formed extensions embracing the intermediate portion of the opposite member of the pair.

7. In a partition structure, a spacing clip comprising a pair of spacing members each consisting of a metal strap having the ends offset to form recesses adapted to engage the sides of spaced studs, and provided with lateral extensions formed upon the edges of the strap intermediate of the recesses and bent outwardly at substantially right angles to receive the opposite strap therebetween, some of said extensions being secured to a framing member and the remaining extensions bent to embrace the opposite spacing member.

8. In a partition structure, a spacing clip comprising a pair of spacing members each consisting of a metal strap having the ends offset to form recesses adapted to engage the sides of spaced studs, and provided with lateral extensions formed upon the edges of the straps adjacent the recess at one end of the member and bent outwardly at substantially right angles toward the open side of the recesses, the extensions of each member being adapted to receive the opposite member therebetween and to be bent into embracing relation to said opposite member.

In witness whereof, I hereunto set my signature.

MARTIN A. CALLAGHAN.
